(57) **ABSTRACT**

A chrysanthemum plant named 'Delphires' characterized by its small sized blooms with red-purple ray florets and prolific branching; natural season flower date 1–4 September; blooming for a period of 6 weeks.

2 Drawing Sheets

1

BACKGROUND OF THE INVENTION

'Delphires' is a product of a breeding and selection program for outdoor pot mums (garden mums) which had the objective of creating new chrysanthemum cultivars with a decorative type flower, a natural season flower date around 1–4 September; blooming for a period of 6 weeks. The new plant of the present invention comprises a new and distinct cultivar of Chrysanthemum plant 'Delphires' is a seedling resulting from the open pollination among groups of chrysanthemum cultivars maintained under the control of the inventor for breeding purposes. The new and distinct cultivar was discovered and selected as one flowering plant by Rob Noodeljik on a cultivated field in Rijsenhout Holland in September 1996. The plant has been asexually reproduced by cuttings in greenhouses at Rijsenhout Holland. The new cultivar has been found to retain its distinctive characteristics through successive propagations.

BRIEF DESCRIPTION OF THE DRAWINGS

The present invention of a new and distinct variety of chrysanthemum is shown in the accompanying drawings, the color being as nearly true as possible with color photographs of this type.

FIG. 1 shows a plant of the cultivar in full bloom.

FIG. 2 shows the various stages of bloom of the new cultivar; and

FIG. 3 shows the various stages of foliage and petiole of the new cultivar.

DESCRIPTION OF THE INVENTION

This new variety of chrysanthemum is of the botanical classification *dendranthema grandiflora*. The observations and measurements were gathered from plants grown outdoor in Rijsenhout, Holland under natural day length and temperature and planted week 22 in 1997 and 1998. The natural blooming date of this crop was 1–4 September (week 35). The plants were observed (directly) during the flowering of this crop. The average height of the plants was 34–36 cms. No growth retardants were used. No tests were done on cold or drought tolerance. This new variety produces small sized blooms with red-purple ray florets.

2

From the cultivars known to inventor the most similar existing cultivar in comparison to 'Delphires' is 'Barbara'. When 'Barbara' and 'Delphires' are being compared the following differences are noticed: The differences of 'Barbara' and 'Delphires' are: (1) Natural flowering date 'Delphires' flowers beginning of September, 'Barbara' around September 25, (2) Vigor. The plants of 'Barbara' are more compact.

The following is a description of the 13-week plant and characteristics that distinguish 'Delphires' as a new and distinct variety. The color designations are taken from the plant itself. Accordingly, any discrepancies between the color designations and the colors depicted in the photographs are due to photographic tolerances.

The color chart used in this description is: The Royal Horticultural Society Colour Chart, edition 1995.

Botanical Classification

Dendranthema grandiflora 'Delphires'

Bud:

Size.—Small, cross-section 1.0 cm height 1.1 cm.

Outside color.—Red-purple 70 B.

Involucral bracts.—2 rows, length 7 mm, width 3 mm.

Involucral bracts among disc-florets.—Not present.

Involucral bracts color.—Green 138 A.

Bloom:

Type.—Decorative.

Height.—Medium.

Size.—Small.

Fully expanded.—4.5–5.5 cm.

Number of blooms per branch.—Approx. 6 blooms per branch.

Performance (on the plant).—6 weeks.

Seeds.—Not produced.

Fragrance.—Typical chrysanthemum.

Color:

Center of flower.—Immature red-purple 61 A (disc when visible yellow-green 154A) Mature red-purple 61 A.

Color of the upper surface of the ray-florets.—Red-purple 61 A.

<i>Color of the lower surface of the ray-florets.</i> —Red-purple 71 B.	<i>Width.</i> —30–32 cm.
<i>Tonality from distance.</i> —A mounded and rich flowering garden mum with red-purple decorative blooms.	<i>Stem color.</i> —Green 138 A.
<i>Discoloration to color.</i> —None.	<i>Stem strength.</i> —Weak.
Ray florets:	<i>Stem brittleness.</i> —Absent.
<i>Texture.</i> —Upper side and under side smooth.	<i>Stem anthocyanin coloration.</i> —Present.
<i>Number.</i> —140–160.	<i>Length of lateral branch.</i> —15–17 cm.
<i>Cross-section.</i> —Concave.	<i>Lateral branch color.</i> —Green 138 A.
<i>Longitudinal axis of the majority.</i> —Straight, outer rows reflexing.	<i>Lateral branch, attachment.</i> —Weak, but not brittle.
<i>Length of corolla tube.</i> —Short.	<i>Branching (average number of lateral branches).</i> —Mounded and prolific with 8–10 breaks after pinching.
<i>Ray-floret margin.</i> —Entire.	<i>Peduncle length.</i> —3.5–4.0 cm.
<i>Ray-floret length.</i> —2.2–2.5 cm.	<i>Peduncle color.</i> —Green 138 A.
<i>Ray-floret width.</i> —0.5–0.7 cm.	<i>Natural blooming data.</i> —1–4 September.
<i>Ratio length/width.</i> —High.	
<i>Shape of tip.</i> —Dentate.	
Disc florets:	<i>Foliation:</i>
<i>Disc diameter.</i> —0.5 cm.	<i>Color.</i> —Upper side green 137 B Under side green 138 B.
<i>Distribution of disc florets.</i> —Numerous, visible at all stages of flowering.	<i>Size.</i> —Small, length 5.0–5.5 cm width 4.0 cm.
<i>Shape.</i> —Tubular.	<i>Quantity (number per lateral branch).</i> —14–16.
<i>Color.</i> —Yellow-green 154 A.	<i>Shape.</i> —Ovate.
<i>Receptacle shape.</i> —Domed raised.	<i>Texture upper side.</i> —Glabrous.
Reproductive organs:	<i>Texture under side.</i> —Pubescent.
<i>Stamen.</i> —Yellow-green, thin 3 mm.	<i>Venation arrangement.</i> —Palmate.
<i>Stamen color.</i> —Yellow-green 144 B.	<i>Shape of the margin.</i> —Serrated.
<i>Pollen.</i> —Some, appears late.	<i>Shape of base of sinus between lateral lobes.</i> —Pointed.
<i>Pollen color.</i> —Yellow 12 A.	<i>Margin of sinus between lateral lobes.</i> —Diverging.
<i>Styles.</i> —Green, thin.	<i>Shape of base.</i> —Attenuate.
<i>Style color.</i> —Yellow-green 144 B.	<i>Apex.</i> —Mucronate.
<i>Style length.</i> —4 m.	
<i>Stigmas.</i> —Yellow-green 144 B.	
<i>Stigma width.</i> —1 mm.	
<i>Ovaries.</i> —Enclosed in calyx.	
Plant:	<i>Differences with the comparison varieties</i>
<i>Type.</i> —A garden mum (pot mum) meant for out door use.	‘DELPHIRES’ ‘BARBARA’
<i>Growth habit.</i> —Spreading.	
<i>Growth rate.</i> —Rapid.	
<i>Height (from soil level).</i> —34–36 cm.	
	Natural flowering date Vigor
	1–4 September Rapid
	25 September Moderate

I claim:

1. A new and distinct variety of chrysanthemum plant as described and illustrated.
